UNITED STATES PATENT OFFICE

2,511,866

INTERMITTENTLY LOADING SCRAPER

George W. Mork, South Milwaukee, Wis., assignor to Bucyrus-Erie Company, South Milwaukee, Wis., a corporation of Delaware

Application December 20, 1945, Serial No. 636,089

12 Claims. (Cl. 37—126)

1

My invention relates to new and useful improvements in wheeled scrapers of the general type shown and described in U. S. Patent No. 2,198,916, granted April 30, 1940, to Earl B. Maloon, to which patent reference is hereby made, inasmuch as this present invention represents an improvement thereon.

In scrapers of that type, the scraper fills and dumps at its front end.

The main frame of such a scraper is pivoted at either its front end or rear end to a wheeled truck, and the digging and spreading depth is determined by raising or lowering the other end of the main frame with respect to a second truck. This is the first operating function.

In Maloon and this present invention, the pivoting is at the front end, and the raising and lowering takes place at the rear end; but this, although very advantageous, is not essential.

The digging blade is carried rigid with the main frame, though this is not essential.

Adjacent the digging blade is pivoted a dirt-extruding curved member, variously termed, and sometimes with, sometimes without, sides of its own. It will here be called a "bowl." Swinging this bowl upward to dump is the second function. Returning this bowl to load carrying position is the third function.

There is also a front closure, usually known as the "apron." Opening this apron (when digging or dumping), and closing it again for carrying, is the fourth function.

Maloon has two controls (ropes), one of which performs the first function (namely depth-control), and the other of which successively performs the fourth function (apron opening) and the second function (dumping). For the third function (bowl return), Maloon depends on a kick-back cam, actuated by the fall of the apron. For my present invention, I prefer to employ three ropes, two of which take the place of Maloon's second rope. Also my first rope performs also the bowl-return function.

To force the first dirt into the scraper requires very little tractive effort; but, as the filling of the scraper progresses, the newly-entering dirt has to push against the dirt already in the scraper, in order to gain entrance, and this requires increasingly more tractive effort as the scraper becomes more and more nearly filled. The present tendency in the trade is to keep increasing the size of scrapers; and, the larger the scraper, the more of an obstacle does the above-mentioned phenomenon become.

Accordingly it is the principal object of my

present invention to devise a very large scraper, which can nevertheless be filled without encountering this obstacle.

A further object of my invention is to provide a scraper in which most of the dirt will be far forward in the scraper, when the scraper is in carrying position, thus putting most of the weight on the traction wheels of the tractor.

In addition to my principal objects, above

stated I have worked out a number of novel and useful details, which will be readily evident as the description progresses.

My invention consists in the novel parts and in the combination and arrangement thereof, which are defined in the appended claims, and of which one embodiment is exemplified in the accompanying drawings, which are hereinafter particularly described and explained.

Throughout the description, the same reference number is applied to the same member or to similar members.

Figures 1 to 5 are side elevations of my scraper, partly in section, taken along the dashed line of Figure 6, and showing my scraper in five successive stages of being loaded.

Figure 6 is a plan view of my scraper, in carrying position.

Figure 7 is a side elevation of my scraper, partly in section, taken along the dashed line of Figure 6, and showing my scraper in carrying position.

Figures 8 and 9 are side elevations of my scraper, partly in section, taken along the dashed line of Figure 6, and showing my scraper in two successive stages of being dumped.

Referring now to these figures, and primarily to Figures 6 and 7, we see that 11 represents a two-wheel tractor, very much conventionalized.

This tractor constitutes the towing-means and the front support for my scraper, through means of the gooseneck 12.

Although I show my scraper as a semi-trailer scraper, and the tractor as a two-wheel balanced tractor, these features are not essential, although

my invention is particularly adapted for use with a semi-trailer scraper, as will be claimed herein.

Built integral with the gooseneck 12, there is the main frame of my scraper, which main frame comprises two side-plates 13, and the necessary

cross-bracing 14, 15 and 16.

Extending across from bottom to bottom of the two side-plates 13, there is a digging-blade 17, preferably carried by cross-bracing 16.

The rear support of my scraper comprises

wheels 18, pillars 19, cross-beam 20, and side-

arms 21, the latter being pivoted to the side-plates 13 of the main frame, preferably on their outside faces, as at 22.

Pivoted to the side-plates 13, preferably on their inside faces, as at 23, is a front apron 24.

Pivoted to the side-plates 13, preferably on their inside faces, as at 25, is a bowl 26. It is to be noted that pivots 25 are well above and ahead of the digging blade 17.

Note also that bowl 26 does not have a complete bottom, the lack being made up by cross-brace 16 and blade 17. Thus it will be seen that the bowl 26, the cross-brace 16, the blade 17, and the apron 24, together constitute a complete bottom closure for my scraper, when bowl and apron are in carrying position, as in Figures 6 and 7; and that with the side-plates 13, this bottom closure constitutes a complete receptacle. For the purposes of my invention, my blade 17 and/or cross-brace 16 will be referred to as a "permanent partial closure."

However, as stated in the preamble hereof, it is not essential that the blade be carried rigidly by the main frame. It could, for example, be carried by the bowl, and the cross-braces could be omitted; in which event the bottom closure would consist entirely of the bowl bottom (including the blade) and the apron bottom. But it would still be important for the bowl pivot 25 to be well forward of, and preferably higher than, the digging blade.

There are three winches, 27, 28 and one not shown, on the tractor. The winch not shown is directly behind No. 27 in all the side-elevation figures.

From the winch not shown, a rope 30 (see Figure 6) extends over a sheave 31 on the gooseneck 12, thence over a sheave 32 supported by cross-brace 14, thence over sheave 33 on the rear support and sheave 34 on the rear of the main frame, thence over deflecting sheaves 35 and 36 on the rear of the main frame, to an anchorage 37 on the bowl 26. In the side-elevation figures, that portion of rope 30 which extends, from the winch not shown, over a sheave 31, to a sheave 32, and these two sheaves, are all not shown, being masked by that portion of rope 42 which extends from winch 27, over a sheave 31 (shown), to a sheave 32 (shown). This rope performs at will the depth control function, and (through constant tension due to the weight of the main frame) constantly tends to perform the bowl return function. This expedient is claimed in U. S. Patent No. 2,304,076, granted December 8, 1942, to Davidson and Hoar.

From winch 28, a rope 38 extends over a sheave 39 on the gooseneck 12, thence over a sheave 41 supported by cross-brace 14, thence over a sheave 40 on the front of the bottom of the apron, to an anchorage 41 supported by cross-brace 14. This rope performs the apron opening function.

From winch 27, a rope 42 extends over a sheave 31 on the gooseneck 12, thence over a sheave 32 supported by cross-brace 14, thence over a sheave 43, to an anchorage 44 supported by cross-brace 14. This rope performs the bowl dumping function.

Sheave 43 is secured to the upper end of a chain 45, consisting of a series of links, pivoted together for bending around the rear end of the bowl, but not for lateral bending. Chain 45 is anchored to the rear bottom of the bowl at 46.

This chain and the curved rear portion of the bowl together constitute a segmental lever, the bowl serving as the segmental cam thereof, and

the chain serving as the flexible member which cooperates with the cam. This construction enables the bowl-tilting force to be applied low and to the rear, thus tilting the bowl well forward to dump into the apron, with undiminished torque. It keeps the sheave 43 out of the dirt and out of possible interference with the ground in digging position. The particular chain construction obviates the need of guides for the chain on the back of the bowl.

Thus we have three ropes performing the four functions essential to this general type of scraper. But, as already stated, my invention does not inhere in any specific number of ropes, nor in the reeving thereof, nor (for that matter) in any particular means of performing these four functions.

For an understanding of the operation of my invention, let us first turn to Figure 1, which shows my scraper in loading position, i. e., with the rear of my main frame lowered so that my blade engages the ground, and with my apron slightly raised so as to permit the entry of dirt into my bowl. The bowl is shown practically filled.

The large size of my apron, as compared with my bowl is to be noted. This is contrary to the conventional relative size of these elements.

When the bowl has been filled as shown in Figure 1, the bowl is tilted forward to dump its contents into the apron as shown in Figure 2.

The bowl is then returned to the position of Figure 1, is again filled, and is again dumped into the apron as shown in Figure 3.

For a third time this cycle is repeated, resulting in Figure 4. The number of these cycles may be more or less than three, depending on the relative size of bowl and apron.

Note how the segmental lever feature enables the forcing of the dirt well forward into the apron.

Finally the bowl is filled, and remains filled, as in Figure 5.

The main frame is then lifted, as in Figure 7, and the scraper is run over the roads to wherever it is to be dumped. Note that the bulk of the load is in the apron, rather than in the bowl as in the conventional scraper of the past. This forward position of the load imposes a considerable weight on the traction-wheels of the tractor, thus increasing the ground-traction.

On reaching the dumping place, the apron is gradually raised thus gradually spilling out its contents, as in Figure 8. The main frame is lowered slightly, so that the blade will spread the dumped material evenly at whatever level is desired.

Finally, as shown in Figure 9, the contents of the bowl is dumped and spread.

The scraper is then hauled back to the digging place, to acquire another load.

Having now described and illustrated one form of my invention, and the operation thereof, I wish it understood that my invention is not to be limited to the specific form or arrangement of parts hereinbefore described and shown.

I claim:

1. In a carry-type earth-moving scraper, the combination of ground-support means; a main frame, supported by the ground-support means, and including side plates; a transverse digging blade carried by the main frame; a partial front closure for the bottom opening between these side plates, consisting of an apron raisably supported by the main frame; a partial rear closure

therefor, consisting of a raisable bowl, said bowl being pivoted to the main frame at a point forward of the blade and being adapted, when lowered, to retain dirt to the rear of the blade; means for raising and lowering the main frame with respect to the ground; means for swinging the bowl forward, to dump into the apron; and means for raising the apron, either to permit filling the scraper, or to permit the exit of excavated material therefrom.

2. In a carry-type earth-moving scraper, the combination of: ground-support means; a main frame supported by the ground-support means, and including side plates; a partial front closure for the bottom opening between these side plates, consisting of an apron raisably supported by the main frame; a partial rear closure therefor, consisting of a raisable bowl pivoted to the main frame; a permanent partial closure carried by the main frame between the front closure and the rear closure, said permanent partial closure being located below the bowl pivot and consisting of a transverse digging blade and a transverse dirt-retaining member adjacent the blade; means for raising and lowering the main frame with respect to the ground; means for swinging the bowl forward, to dump into the apron; and means for raising the apron, either to permit filling the scraper, or to permit the exit of excavated material therefrom.

3. A scraper according to claim 1, further characterized by the fact that the bowl is pivoted to the main frame at a point above the blade.

4. A scraper according to claim 1, further characterized by the fact that the blade constitutes a permanent partial closure between the front closure and the rear closure.

5. A scraper according to claim 1, further characterized by the fact that the blade constitutes a part of a permanent partial closure between the front closure and the rear closure.

6. A scraper according to claim 1, further characterized by the fact that adjacent the blade there is a transverse plate carried by the main frame and constituting at least part of a per-

manent partial closure between the front closure and the rear closure.

7. A scraper according to claim 1, further characterized by the fact that the bowl swinging means comprises a segmental lever.

8. A scraper according to claim 1, further characterized by the fact that the bowl swinging means comprises a segmental lever, of which the flexible element is anchored to the bottom rear of the bowl, and the rear of the bowl serves as the segmental cam which cooperates with the flexible element.

10 9. A scraper according to claim 1, further characterized by the fact that there is means biasing the initiation of the return of the bowl from dumping position.

15 10. A scraper according to claim 1, further characterized by the fact that the apron is sufficiently larger than the bowl, so as to hold a plurality of bowl contents.

20 11. A scraper according to claim 1, further characterized by the fact that the ground support means consists of a rear support and means to support the front of the scraper on a towing 25 tractor.

12. A scraper according to claim 1, further characterized by the fact that the ground support means consists of a rear support and means to support the front of the scraper on a towing 30 tractor, and that the apron is substantially larger than the bowl, whereby the scraper, when filled, imposes a considerable portion of its load on the ground-engaging tractive device of the tractor, thereby increasing the traction thereof.

35 GEORGE W. MORK.
